CLOTHES TREE OR THE LIKE

Nicholas Davenport, Bronx, N. Y.

Application April 21, 1953, Serial No. 24,612

Term of patent 14 years

(Cl. D33—8)

To all whom it may concern:

Be it known that I, Nicholas Davenport, a citizen of the United States and a resident of the county of Bronx and State of New York, have invented a new, original, and ornamental Design for Clothes Tree or the like, of which the following is a specification, reference being had to the accompanying drawing, forming a part hereof.

Fig. 1 is a front, elevational view of a clothes tree or the like, showing my new design, and Fig. 2 is a side view thereof.

I claim:

The ornamental design for a clothes tree or the like, as shown.

NICHOLAS DAVENPORT.
